UNITED STATES PATENT OFFICE.

MORTIMER J. SILBERBERG, OF CHICAGO, ILLINOIS.

TIE-PLATE.

1,100,848.

Specification of Letters Patent. Patented June 23, 1914.

Application filed March 28, 1914. Serial No. 827,947.

To all whom it may concern:

Be it known that I, MORTIMER J. SILBERBERG, a citizen of the United States, and resident of Chicago, in the county of Cook and State of Illinois, have invented certain new and useful Improvements in Tie-Plates, of which the following is a specification.

My invention relates to railway track construction and has particular reference to a novel tie plate and clip particularly adapted for use with screw spikes.

It is common practice on many railroads to place beneath the rails on each tie a tie plate in order to increase the bearing surface between the rail and the plate. Such plates have taken many forms but few of those being adapted for use with screw spikes. In order to utilize this desirable form of fastening a special form of plate must be provided. Such a plate must provide for a secure and extended bearing for the head of the screw spike, such bearing being preferably in the form of a plane surface whereby the flange or head of the spike may be rotated freely thereon.

In many of the screw spike tie plates provision is made for direct contact between the rail and the head of the spike. This requires that the under surface of the spike shall be conical or at least inclined to correspond to the angle of the top surface of the rail base. Thus only a line or point contact is secured between the spike and rail.

An object of my invention is to provide means whereby an extended bearing surface is secured, and also to provide means for utilizing a screw spike having a flange with a horizontal under surface. These results are secured by the use of a clip such as shown. However, due to inequalities and permissible variations, such a clip in order to certainly engage the rail base must have a single point of contact with the tie plate, which point preferably acts as a fulcrum. Thus a broad bearing is secured between clip, rail base and spike, and the clip is certain to engage the rail under all conditions of variation in material.

In the accompanying drawings, Figure 1 is a transverse section of a railway rail

with which my novel tie plate is associated, and, Fig. 2 is a plan view of the same.

Referring more particularly to the drawings it will be seen that I preferably provide a plate consisting of a body portion 10, 55 having transverse upstanding flanges 11, against which the base of the rail may abut. Thus the rail is securely held in transverse alinement without direct contact with the screw spike or the head thereof. In the 60 body 10, of the plate and located at the sides of the flanges 11, are apertures within which the screw spikes 12 are located. These spikes are each provided with a squared head 13, and an annular horizontal flange 14. Interposed between the tie plate and the flange 14 of the spike is a clip 15, provided with an extension 16, overlying the base 17, 65 of a rail. The lower surface of the clip 15 is shaped to provide substantially line contact with the tie plate in order to assure a perfect engagement thereof. As shown, the lower face of the clip is diagonal with relation to the top thereof, as at 18, providing the contact point 19. From the point 19, 70 the clip extends upward, terminating in the reduced extension 16, which overlies the rail. The upper surface of the clip 15 is seen to be a plane surface and thus provides a bearing for the flange 14 of the 75 screw spike.

I claim:

1. A tie plate having a rail abutting flange, a clip superposed on said plate, overlying said flange and engaging a railroad rail, and a screw spike passing through said clip and said plate, substantially as described. 85

2. In combination, a tie plate having a rail abutting flange and an aperture for a spike, a clip superposed on said plate and projecting over said flange, said clip being constructed to provide substantially line contact with said plate, and a screw spike passing through said clip and said plate, substantially as described. 90

3. In combination, a tie plate having a rail abutting flange and a spike aperture, a clip having a substantially horizontal plane upper surface for contact with a corresponding surface on the head of a screw spike, the 95 100

lower surface of the clip being constructed to provide for line contact with the plate, and a screw spike projected through said clip and said plate, substantially as described.

4. In combination, a tie plate having a rail abutting flange and a spike aperture, a clip and a screw spike extended through said clip and said plate, said clip having its

lower surface beveled to correspond substantially to the angle of inclination of the upper surface of a rail base, said clip having substantially line contact with said plate, substantially as described. 10

MORTIMER J. SILBERBERG.
